ATTORNEY

UNITED STATES PATENT OFFICE.

CHARLES W. LAIR, OF BETHEL, MISSOURI.

EJECTING-PENHOLDER.

1,244,343.

Specification of Letters Patent. Patented Oct. 23, 1917.

Application filed June 15, 1917. Serial No. 174,968.

To all whom it may concern:

Be it known that I, CHARLES W. LAIR, a citizen of the United States, residing at Bethel, in the county of Shelby and State 5 of Missouri, have invented new and useful Improvements in Ejecting-Penholders, of which the following is a specification.

My invention relates to ejecting penholders and has for its primary object to provide an ejecting mechanism of a simple and efficient character.

A further object of my invention is to provide a penholder which is adapted to retract the pen into the penholder so that 15 the penholder may be carried around in the pocket, means being provided on said penholder whereby the pen may be ejected by the manipulation of the same mechanism which serves normally to retract the same 20 within the penholder.

With these and other objects in view which will be hereinafter fully described and particularly pointed out in the claim, the invention consists in the novel construction 25 and arrangement of parts illustrated in the accompanying drawing forming a part of this specification, in which:—

Figure 1 is a side elevation of a penholder embodying my invention with the pen extending in writing position,

Fig. 2 is an enlarged longitudinal section showing the parts in the same position as designated in Fig. 1,

Fig. 3 is an enlarged transverse section of 35 the device on the line $a-a$ of Fig. 1.

Like characters of reference indicate like parts in the various views.

In the drawings 1 designates a tubular pen stock which is provided at its one end 40 with a handle 2 of usual construction. A pen nib retaining member 3 is mounted for longitudinal movement within said pen stock. The pen stock is provided with a longitudinal slot 4, and a sleeve 5 which is mounted upon the outer surface of the pen stock 1 for longitudinal movement, and is connected to the pen nib retaining member 45 by means of pins 6. The pen nib retaining member comprises a circular sleeve member 7, to which the pins 6 are secured, and a

forwardly extending portion 8, which is curved to fit the nib of a pen 9, and which lies adjacent the inner surface of the sleeve 7. The inner walls of the portion 8 have a longitudinal slot 10 formed therein for purposes presently to be described. 55

A bracket 11 is mounted within the pen stock 1 which is disposed near the upper end thereof, and a bar 12 is pivoted on the bracket 11 at a point intermediate its ends 60 and extends toward the lower end of the pen stock. A shoulder 13 is formed upon the extending end of said bar and is adapted to engage the lower end of the pen 9 as the pen nib retaining member 3 is moved downwardly into the pen stock, the slot 10 allowing said shoulder to engage said pen until it is ejected from the retaining member. A plunger 14 is mounted upon the lower end 65 of the bar 12 and extends through a hole 70 15 in the pen stock and terminates in a knob 16 on the outside of the pen stock. A spring 17 is secured upon the outside of the pen stock and engages the under surface of the knob 16, and through the plunger 14 75 serves to normally position the bar 10 so that the shoulder 13 thereof is in a disengaged position relative to the pen 9.

By the above described mechanism it will be noted that an ejecting penholder is provided which will allow the pen to be retracted within the handle, means being provided whereby the pen may be forced from its retaining member as it is moved to retract the same within the pen stock. 80 85

Having thus fully described my invention, I claim:—

A penholder comprising a stock, a sleeve 90 slidably mounted therein, a retainer attached to the sleeve and adapted to carry a pen, a bar pivoted in the stock and having an end portion passing through the side thereof, said bar having a shoulder which is located in the sleeve and a spring engaging the bar and normally holding the shoulder thereof 95 out of the path of movement of the pen carried by the retainer.

In testimony whereof I affix my signature.

CHARLES W. LAIR.
